DESIGN FOR A CHRISTMAS TREE ORNAMENT OR THE LIKE

Hugo Hoffmann, New York, N. Y., assignor to Elite Hand Painting Corporation, New York,
N. Y.

Application February 12, 1943, Serial No. 109,532

Term of patent 14 years

To all whom it may concern:

Be it known that I, Hugo Hoffmann, a citizen of the United States, residing at New York city, in the county of New York and State of New York, have invented a new, original, and ornamental Design for a Christmas Tree Ornament or the like, of which the following is a specification, reference being had to the accompanying drawings, forming a part thereof.

In the drawings:

Fig. 1 is a front view of a Christmas tree ornament or the like, showing my new design;

Fig. 2 is a side view thereof, and

Fig. 3 is a rear view thereof.

I claim:

The ornamental design for a Christmas tree ornament or the like, as shown.

HUGO HOFFMANN.
